US00D995475S

(12) **United States Design Patent** (10) **Patent No.:** **US D995,475 S**
(45) **Date of Patent:** **** Aug. 15, 2023**

(54) **HEADPHONES**(71) Applicant: **Apple Inc.**, Cupertino, CA (US)(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)(73) Assignee: **Apple Inc.**, Cupertino, CA (US)(***) Term: **15 Years**(21) Appl. No.: **29/882,405**(22) Filed: **Jan. 13, 2023****Related U.S. Application Data**

(63) Continuation of application No. 29/746,598, filed on Aug. 14, 2020, now Pat. No. Des. 975,672.

CLAIM

The ornamental design for headphones, as shown and described.

DESCRIPTION

FIG. 1 is a top front perspective view of headphones showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof.

FIG. 7 is a top view thereof; and,

FIG. 8 is a bottom view thereof.

The broken lines in the figures show portions of

phones that form no part of the claimed design.
